FIG. 9

Inventor

FRED A. CONTERMAN.

A cross-sectional view of a mechanical assembly, likely a pump or valve component. The assembly is labeled FIG. 12. Key parts are numbered: 26A, 52, 53, 44, 55, 56, 48, 51, 33, 49, 47, 43, 39, 38, 31, 36, 34, 50, 42, 41, and 37. The assembly consists of a housing with various internal parts, including a piston-like element and a valve mechanism. The numbers likely correspond to specific parts or features described in the patent specification.

12 Claims. (Cl. 68—253)

1

This invention relates to improvements in wringers and more particularly to wringers of the type generally associated with domestic washing machines.

Wringers of this type are generally provided with safety mechanisms that permit instant release of the roll pressure in case of an emergency. Although many different kinds of manually operated release mechanisms have been developed, these mechanisms have not been so designed as to be entirely dependable in an emergency. For instance, some of these mechanisms have been of such proportions and location as to require a wringer operator to exert considerable force in effecting release. In other structures, the release mechanism, although accessible, has been so located that the parts thereof deteriorated from an accumulation of soap residue, lint, etc., to such an extent that in an emergency the mechanism would not release or, perhaps, release only under application of considerable force by the wringer operator.

To provide an adequate emergency release mechanism for wringers, it is essential that a suitable actuator be so disposed as to be conveniently accessible from both sides of the wringer, and of such proportions as to be capable of actuation by almost any movable portion of the operator's body, such, for example, as hand, arm, shoulder, etc. Wringing rolls are held in pressure relationship by means of a strong spring, and in an emergency the release mechanism is tripped to relieve the pressure between these rolls. During this relieving movement some part or parts of the wringer must be displaced and these parts frequently take the form of a wringer enclosure or casing. Thus, when the release mechanism is actuated, the roll spring is released with such force and violence that the movable parts of the enclosure constitute a serious hazard to the operator. This is particularly true when it is considered that the release mechanism is generally only actuated in an emergency, and under such conditions the operator is extremely close to the wringer and is incapable of stepping back or in any other way avoiding these moving parts when they are released. Of course the purpose of providing movable parts is not only to give space within the wringer enclosure for movement of the roll spring, but also to provide adequate mechanical advantage in again placing the spring under tension.

The present invention is directed to the provision of a wringer structure that, among others, has for an object the provision of a safety roll re-

2

lease mechanism of such proportions and location as to be capable of instantly releasing the roll spring under any and all conditions of wringer use.

5 Another object of the invention lies in the provision of an actuator for the release mechanism so located as to be readily accessible from either side of the wringer and so easily operable that the release mechanism may be tripped by slight movement of almost any part of the body of the operator into contact with the actuator.

Another object of the invention lies in the provision of a roll release mechanism in combination with roll stop means in which the operative pressure of the rolls is entirely relieved prior to disconnection of the driving means.

Another object of the invention lies in the provision of a release mechanism in which the trip members are only indirectly subjected to the force of the roll pressure means.

Another object of the invention will be found in the provision of reset means for the release mechanism that is easily operable due to provision of a high mechanical advantage and at the same time is movable through so short a distance as not to constitute a hazard to the operator.

Another object of the invention lies in the provision of a release mechanism that is operable not only to relieve pressure throughout the roll length but to allow the rolls to become displaced and separable relative to one another.

35 A further important object of the invention lies in the provision of simplified roll drive connection which facilitates ready assembly or disassembly of a wringer with respect to the drive head, and in no way interferes with or complicates the structure of the release mechanism or actuator for such mechanism.

40 Other objects and advantages will be more fully understood from a consideration of the following specification, taken in conjunction with the accompanying drawings; and in which

45 Fig. 1 is a side elevational view of a wringer embodying one form of the invention, parts being broken away to disclose the connection between the cover and roll pressure spring;

Fig. 2 is a plan view, partly broken away, of the structure shown in Fig. 1;

50 Fig. 3 shows a position of the cover of the wringer enclosure during operation of the roll release mechanism;

Fig. 4 shows the final position of the cover following operation of the release mechanism;

55 Fig. 5 is a plan view of the wringer, parts being

broken away to show structural details of the roll release mechanism;

Fig. 6 is an enlarged side elevational view, partly broken away and sectioned, and discloses the release mechanism in position for operation of the wringer;

Fig. 7 is a view similar to Fig. 6 and shows the release mechanism actuated to disengage the roll clutch and raise the wringer cover;

Fig. 8 is an enlarged fragmentary view showing the position of the parts of the release mechanism as they move into resetting position;

Fig. 9 is a vertical sectional view taken substantially on the line 9-9 of Fig. 6 and shows the release actuator in neutral position;

Fig. 10 is an end view of the trip mechanism, being shown in either of two positions of operation in solid and dotted lines;

Fig. 11 is a vertical sectional view taken substantially as indicated by the line 11-11 of Fig. 6;

Fig. 12 is a fragmentary detail view of the roll clutch mechanism;

Fig. 13 is a side elevational view of a modification of the invention wherein the actuator for the roll release is carried by the drive head;

Fig. 14 is a vertical sectional view of the structure shown in Fig. 13, being taken substantially as suggested by line 14-14 of this figure; and

Fig. 15 is an enlarged detail of the structure shown in Fig. 13, showing the method of assembling the wringer on the drive head and the position of the release actuator when the wringer is assembled.

Referring to the drawing, the reference numeral 10 is employed to generally designate a wringer in which is embodied one form of the invention. The wringer is carried by a reverse gear housing 11 which in turn is swivelable on a drive housing 12. As is conventional, the housing 12 extends downwardly of one side of the washing machine with which the wringer is associated. The wringer 10 includes a casing 13 having side walls 14 and 16, and an end wall 17. The other end of the casing is styled to blend with the contour of the reverse gear housing 11. The side walls 14 and 16 of the casing are fitted with appropriate drain aprons 18 which, in the present disclosure, conceal all but a small portion of the lower roll 19 as well as the ends of the upper roll 21.

Within the casing 13 is a frame that includes end uprights 22 and 23. Suitable channels in these uprights position bearing blocks 24 and 24a which receive the supporting shafts 26 and 26a of the rolls 19 and 21 respectively. In the present disclosure, roll 19 being the driving roll, shaft 26a extends through upright 23 for connection with the driving mechanism enclosed within the housing 11. A leaf spring 27 is provided, the ends thereof resting upon the uppermost bearing blocks 24, and when pressure is applied through operation of a conventional connector 25 and spring tension knob 28, the upper roller 21 is brought into desired pressure relationship with the lower roll 19.

Mounted in the housing 11 is a reverse drive mechanism, control of which is had through a lever 29. In its lowermost position this lever disengages the drive from the rolls and when turned into horizontal position in either direction, causes the rolls to rotate in one direction or the other. For purposes of the present invention, the roll drive is indicated by the shaft 31 supported in a bearing 32. Set screw 33, riding in

a groove in the shaft 31, prevents axial movement thereof. Although the lever 29 serves to control rotation of the roller drive shaft 31, an emergency clutch is provided between the shaft 26a and drive shaft 31. This clutch operates to disengage the roller drive when, in an emergency, a mechanism is actuated to release the spring pressure of the rolls. Adjacent its end, shaft 31 is fitted with a drive pin 34 that is received within grooves 36 of a clutch sleeve 37. A ring 38 is mounted on this sleeve and serves to position one end of a sleeve encircling spring 39. The other end of the spring bears against a throw-out collar 41 having an annular groove 42. The collar is prevented from being displaced from the sleeve by a lock ring 43 but is, however, movable from adjacent the lock ring toward the ring 38, to compress spring 39. A shaft 44 extends transversely of the housing 11, one end projecting beyond the housing wall and being fitted with a reset lever 46. This shaft mounts a throw-out member 47 for the clutch above described, which member takes the form of a pair of arms 48 connected by an integral strap 49. The lower or free ends of the arms are fitted with pins 50 which project from opposite sides into the groove of the clutch collar 41. Remote from the strap 49, the member 47 includes identical wing-like extensions, in each of which is formed an arcuate slot 51. Between these extensions a trigger member 52 is mounted on and keyed to shaft 44. This member includes a central arm 53 that terminates in a trigger finger 54, as well as a pair of arms 55 which extend substantially at right angles to arm 53. A pin 56 connects the free ends of arms 55 and extends sufficiently beyond these arms to project into and through slots 51 of the member 47. A spring 57 encircles shaft 44, one end being secured in a part of the framing of the casing 11, and the other end engaging one end of the pin 56. The spring is intended to urge the pin 56 generally downwardly in the direction suggested by a comparison of Figures 6 and 7 of the drawing.

Adjacent the trigger 54, arm 53 is fitted with rollers 58. These rollers contact the cam edges 59 of a channelled rocker member 60 that forms part of a trip mechanism 61. The member 60 is pivotally mounted on a shaft 62 and may be centrally positioned by a sleeve or boss 63 on one side, and a further boss or sleeve 64 on the other side, together with a spring 66. This spring is so engaged with the member as to urge it into the tilted position shown in Figure 7. At one end the sides of the member 60 are formed with upturned arms 61. Positioned on the upper surface of the member is a tilt plate 68 of a size to fit between arms 61. One end of this plate extends beyond the end of the member and terminates in an end flange 69, formed with an upwardly opening V-slot that provides identical cam surfaces 71. Adjacent the flange 69 are upstanding arms 70 that align with and are located between arms 61. The other end of this plate is formed with an aperture 72. Washers 73 seat the ends of a spring 74. An opening 76 is formed in the horizontal portion of the member by bending out a tab that forms an upright 77. This upright projects through the aperture 72, and spring 74, and is fitted with spring securing means 78. Substantially midway of the length of the plate 68 is an aperture 79 that aligns with one end of the aperture 76 of the member 60. The size of apertures 76 and 79 is such that the trigger 54 may project therethrough. The upturned arms

67 and 70, after mounting plate 68 on the upper surface of the member, are connected by a shaft 81. This shaft, together with the arrangement of spring 74, serves to prevent displacement of the plate, but at the same time permit pivotal movement with respect to the member.

Attached to the upright 23 of the frame of the wringer by a stud 82 is a rocker plate 83. This plate includes arms 84 that extend beyond the sides of the wringer casing and serve to mount corresponding ends of a pair of trip levers or bars 86 located in close proximity with the upper roll 21. A roller 87 is mounted on the upper end of the plate 83 and projects into the V-slot that forms cam surfaces 71. A spring 88 connects the shaft of roller 87 with a pin 89 carried by the frame 23. The purpose of spring 88 is to return the plate 83 to the vertical position shown in Figure 9, following pivotal movement thereof into either the dotted or solid line position shown in Figure 10.

The other end of the wringer casing 13 may be formed with inwardly extending bosses 91 which, through studs 92, mount the flanged ends 93 of a channel member 94. This member extends upwardly above the end of the casing 13. A downwardly directed extension 97 of the channel member 94 pivotally supports the base portion of a rocker plate 98 through a pin structure 99. The plate 98 includes arms 101 that extend in opposite directions beyond the walls of the casing and secure the other ends of bars 86. As may readily be understood from the structure described, movement in almost any direction of either bar 86 will rock plate 83, and such movement causes tilting of plate 68 by reason of contact of roller 87 therewith.

The structure thus far described is provided with a cover 102. This cover extends not only over the wringer structure enclosed within the casing 13, but also over the gear housing 11. The upper edge of housing 11 and casing 13 may be flanged or lipped to properly seat the rim 103 of the cover. As shown in the drawing, the member 68 is located in the upper portion of the gear housing 11 and is centrally, pivotally mounted on shaft 62. The end of this member, remote from plate 68, engages flanges or arms 104 of the cover through pin 106 to provide relative pivotal movement. The other end of the cover includes a pair of spaced arms 107 that are connected adjacent their lower ends by pin 108. This pin, when the release mechanism is set, is engaged with the notches 96 of the side walls of channel 94. Between the arms 107 and attached to the pin 108 is a plate 109. The plate is of a width to be located between the sides of the channel 94, being guided by stop plate 95, and, with the cover 102 in closed position, extends into the space between bosses 91, terminating in a cross-head 111. This plate is of a length to limit upward travel of this end of the cover by striking against stop plate 95 when the release mechanism has been actuated to relieve pressure of the rolls 19 and 21 (see Figure 4).

The structure described has contemplated provision of parallel trip levers or bars on each face of the wringer and also a mechanism actuated by these bars for upsetting the member 60. The rocker plate 83, being carried by the wringer upright 23, necessarily forms a part of the wringer structure, although actually it is a part of the roll pressure release mechanism. Under certain circumstances it may be found not only desirable, but perhaps necessary to assemble the entire roll

pressure release mechanism within the housing 11 and thus enable the interchangeable mounting of several different types of wringers. Figures 13 to 15, inclusive, of the drawing illustrate one manner in which this may be accomplished. The drive housing in this modification, together with those parts of the release mechanism carried thereby, are identical with those previously described, with the exception that the end of plate 68 terminates not in an upwardly opening V-slot but, rather, in a flange 112 having cam surfaces 113. In this structure, the end of the housing 11 is closed by a plate 114 and supported at the upper end of this plate is a pin 116. This pin mounts a rocker plate 117 that includes opposed arms 118 extending beyond the side edges of the housing 11 and fitted with knobs 119. Rollers 121 are mounted on the rocker plate 117, one roller contacting each of the cam surfaces 113.

The wringer structure 122 of this modification includes an end wall or upright 123, similar to the upright 23 of the previous modification, and the rolls being identical, the lower roll 19 has a drive shaft 26A that extends beyond the upright 123. Studs 124, in the upright 123, are engageable with the end plate 114 of the housing. From the foregoing, and examination of the drawing pertaining to this modification, it is evident that the release mechanism is carried in its entirety by the housing 11, and when it is desired to mount a wringer, it is merely necessary to project the roll shaft 26A into the open end of the clutch member and engage the studs 124 with threaded openings in the plate 114. The cover 102 may or may not include the plate 109 previously described, but if such plate is attached, the cross-head may be swung into place after mounting the wringer and during closing the cover and setting the release mechanism.

To more clearly bring out the features of the present invention, description of the assembly, setting, and operation of the structure is as follows: It will be noted that the wringer is first attached to the reverse gear housing 11 by placing the end upright 23 against a corresponding upright of the housing and securing these uprights by studs. As has already been mentioned, the upright 23 of the wringer mounts rocker plate 83 and attendant parts, which include roller 87. Thus, when the wringer is positioned, roller 87 projects into and lies in the base of the V-shaped flange in the manner indicated in Figure 9 of the drawing. Of course, simultaneously with this assembly, the drive shaft 26A is projected into and is engaged with clutch sleeve 37.

For purposes of description, it may be assumed that the wringer is in operation, the parts, with the exception of lever 23, being in the position shown in Figures 1 and 6. Should the operator of the wringer become caught in any way, it is merely necessary to exert slight pressure against either of the bars 86. Such pressure swings rocker plate 83 and causes the roller 87 to bear upon one or the other cam surfaces 71, thus tilting plate 68 in such a manner that the trigger 54, under tension of spring 57, will move in an arc about shaft 44. Movement of the trigger and arm 53 of which it is a part, turns the reset lever 46 and at the same time rollers 58 move along the cam edges 59, allowing the member 69 to pivot about its shaft 62. The member, being connected with the cover 102, receives its pivotal drive from the roll spring 27 which, as is common with wringers, is placed under tension by turning down the con-

ventional tension knob 28. It is to be particularly noted that as the member 60 turns about its pivotal point, its connection with the cover is such that one end thereof moves upwardly through an arc about the shaft 62, and is thus moved in a lengthwise direction as well. Operation of the mechanism at this point is indicated by the position of the cover in Figure 3 of the drawing. Continued turning of the member and endwise movement of the cover removes pin 108 from the notches 96, and thus the other end of the cover becomes disengaged from the wringer enclosure (see Figure 7). With both ends of the cover freed, said cover is raised at the trip end only to an extent permitted by the trip member 60, and at the other end, to the extent permitted by the plate 109 (see Figure 4). With the cover in raised position, tension of the roll spring 27 is entirely relieved. During movement of the trigger member 52 from the position of Figure 6 to that of Figure 7, arms 55 thereof, carrying pin 56, have moved from the top to the bottom of slots 51 of throw-out member 27 and, with continued movement, pin 56 causes movement of the arms to an extent to withdraw the clutch sleeve 37 from engagement with the drive pin 34. It is thus evident that, as the roll pressure is relieved, the emergency clutch is thrown out and rotation of the rolls ceases.

It has been mentioned that due to the strength of the roll spring considerable movement of the roll releasing parts is necessary in order that a sufficient mechanical advantage may be obtained to reset the mechanism and again place the roll spring under proper tension. In the present disclosure the wringer cover 102 does not of itself constitute a lever by which to reset the roll spring but, rather, by its connection at one end, through member 60, cam surfaces 59, rollers 58, and arm 53, with the reset lever 46, provides such mechanism that an operator of the wringer may, without difficulty, turn the reset lever from the position of Figure 7 to that of Figure 6. During the resetting operation the member 60 again assumes its substantially horizontal position, this movement being generally indicated by the dotted and solid lines of Figure 8. The trigger 54 swings upwardly through slot 79 of plate 68 and, because the member has assumed a horizontal position, plate 68 likewise assumes such position, spring 74 functioning to assure this movement. Similarly, the pin 56, carried by arms 55, is moved upwardly of the slots in the extensions of member 47 and thus causes this member to move the throw-out collar to increase the tension of spring 39 and thereby urge sleeve 37 into engagement with the drive pin 34.

In the modification shown in Figures 13 to 15 the release and reset mechanism operates in the manner above described. However, it is to be noted that the release mechanism, with the exception of one end of the cover 102, is carried by the housing 11. Thus, any of several types of wringer structures may be utilized with the release and reset mechanism described. In this modification, however, somewhat less facility for tripping the mechanism is provided, since only the knobs 119 serve this purpose and these knobs are at substantially the point of connection of the wringer proper with the housing 11. The fact that this modification provides a pair of rollers 121 as against the single roller 87 heretofore described in no way changes the ease with which the mechanism may be tripped or reset.

Although applicant has shown and described

only two forms of his release and reset mechanism for wringers, it will be understood that variations of the structure such, for example, as shown in the modification of Figures 13 to 15, inclusive, are contemplated insofar as they are within the spirit and scope of the invention as set out in the annexed claims.

Having thus set forth my invention what I claim as new and for which I desire protection by Letters Patent is:

1. In a wringer structure having a frame and a pair of cooperating rolls mounted therein, a housing mounting said frame and having drive means operatively associated with said rolls, pressure means for said rolls, a cover enclosing the top of said frame and housing and, in closed position, applying said pressure means to said rolls, a latch mechanism for said cover comprising a member pivotally mounted in said housing and associated with and operable to define a path of movement and position of said cover when moved under impulse of said pressure means into an open position, a plate carried by said member, a spring actuable trigger held in set position by said plate and associated with said member to prevent movement thereof, and manually operable means for actuating said plate to release said trigger.

2. In a wringer structure having a frame, a pair of cooperating rolls mounted in said frame, a housing mounting said frame and enclosing a clutch and drive means operatively associated with said rolls, pressure means for said rolls, a cover for said frame and housing, said cover in closed position applying said pressure means to said rolls, a latch mechanism comprising an operable member associated with one end of said cover, said member serving to define a path of movement of said cover when moved under impulse of said pressure means into an open position, operable means securing said member in cover closed position, manual means adjacent said rolls having operative association with and adapted to actuate the member securing means to release said member for movement into cover open position, said member securing means including an oscillatable member having a lost motion connection with said clutch.

3. In a wringer structure having a frame, a pair of cooperating rolls mounted in said frame, a housing mounting said frame and enclosing a clutch and drive means operatively associated with said rolls, pressure means for said rolls, a cover for said frame and housing, said cover in closed position applying said pressure means to said rolls, a latch mechanism comprising an operable member associated with one end of said cover, said member being movable to define a path of movement of said cover into an open position or closed position, a trigger member means on said member engageable by said trigger member to secure said member in cover closed position under tension of said pressure means, said trigger member being operatively engaged with said clutch, and a release bar adjacent said rolls operable to move said member means to release said trigger member and operate said clutch.

4. In a wringer structure having a frame, a pair of cooperating rolls mounted in said frame, a housing mounting said frame and enclosing a clutch and drive means operatively associated with said rolls, pressure means for said rolls, a cover enclosing the upper part of said frame and housing, said cover in closed position applying said pressure means to said rolls, a latch mecha-

nism comprising a trip plate, trigger and pivotal member mounted in said housing, said member having connection with said cover and in one position thereof holding said cover in closed position, said trigger being releasably held in a set position by said plate and in turn securing said member in cover closed position, said trigger also having connection with said clutch means and being operable, when released, to disengage said drive means from said rolls.

5. In a wringer structure having a frame, a pair of cooperating rolls mounted in said frame, a housing mounting said frame and enclosing a clutch and drive means operatively associated with said rolls, pressure means for said rolls, a cover enclosing the top of said frame and housing, said cover in closed position applying said pressure means to said rolls, a latch and reset mechanism mounted in said housing, said mechanism comprising a trip plate, a trigger member releasably held in a set position by said plate, a pivot member connected with and serving to control movement of said cover, said pivot member being secured in cover closed position by association with said trigger member, manually operable means for upsetting said trip plate to release said trigger member and free said pivot member for movement into cover open position, and further means for moving said trigger member to return said pivot member to cover closed position and engage said trigger member with said plate.

6. In a wringer structure having a frame, a pair of cooperating rolls mounted in said frame, a housing mounting said frame and enclosing a clutch and drive means operatively associated with said rolls, pressure means for said rolls, a cover enclosing the top of said frame and housing, said cover in closed position applying said pressure means to said rolls, a latch mechanism mounted in said housing, said mechanism comprising a trip plate, a trigger member releasably held in a set position by said plate, a pivot member connected with and serving to control movement of said cover, said pivot member being secured in cover closed position by association with said trigger member, said trigger member being operatively associated with said clutch means, manually operable means for upsetting said plate to release said trigger member and free said pivot member for movement into cover open position under impulse of said pressure means, said trigger, when released, actuating said clutch means to disengage said drive means from said rolls.

7. In a wringer structure having a frame, a pair of cooperating rolls mounted in said frame, a housing mounting said frame and enclosing a clutch and drive means operatively associated with said rolls, pressure means for said rolls, a cover enclosing the top of said frame and housing, said cover in closed position applying said pressure means to said rolls, a latch and reset mechanism mounted in said housing, said mechanism comprising a trip plate, a trigger member releasably held in a set position by said plate, a pivot member connected with and serving to control movement of said cover, said pivot member being secured in cover closed position by association with said trigger member, said trigger member being operatively associated with said clutch means, manually operable means for upsetting said plate to release said trigger member and free said pivot member for movement into cover open position under impulse of said pressure means, said trigger, when released, actuating said clutch means to disengage said drive means from

said rolls, and further means for moving said trigger member to return said pivot member to cover closed position and engage said trigger member with said plate.

5. 8. In a wringer structure having a frame, a pair of cooperating rolls mounted in said frame, a housing mounting said frame and enclosing a clutch and drive means operatively associated with said rolls, pressure means for said rolls, a cover enclosing the top of said frame and housing, said cover in closed position applying said pressure means to said rolls, a latch and reset mechanism mounted in said housing, said mechanism comprising means for securing said cover in closed position against tension of said pressure means, a trigger having a set position in which to engage and secure said means in cover closed position, a manually operable trip for said trigger, said trigger including delayed action means operably associated with said clutch means, and a lever operable to reset said trigger and move said means into cover closed position.

9. In a wringer structure having a frame, a pair of cooperating rolls mounted in said frame, 25 a housing mounting said frame and enclosing a clutch and drive means operatively associated with said rolls, pressure means for said rolls, a cover enclosing the top of said frame and housing, said cover in closed position applying said pressure means to said rolls, a latch and reset mechanism mounted in said housing, said mechanism comprising a trip plate, a trigger member releasably held in a set position by said plate, a pivot member connected with one end of said 30 cover and defining a path of movement into and out of closed position, a catch for securing the other end of said cover to said frame, said pivot member being operatively associated with said trigger member and movable, under impulse of 35 said pressure means, to adjust said cover to release said catch, said trigger member including delayed action means operable on said clutch means, and a lever operable to reset said trigger member and return said pivot member and cover 40 to cover closed position.

10. In a wringer, a frame, wringer rolls within the frame, a support for the frame, a clutch within the support, and drive means associated with the clutch for operating the rolls; in combination with pressure means for the rolls, a cover for the top of said frame, said cover effecting movement of said pressure means to apply pressure to said rolls, when said cover is moved to closed position, release and reset mechanism, and 55 manually operable means exteriorly of said cover for actuating the release and reset mechanism, said release and reset mechanism including a swingable member and a lost motion clutch control member, whereby movement of the clutch is 60 effected when the cover is moved.

11. In a wringer, a frame, wringer rolls within the frame, a support for the frame, a clutch within the support, and drive means associated with the clutch for operating the rolls; in combination with pressure means for the rolls, a cover for the top of said frame, said cover effecting movement of said pressure means to apply pressure to said rolls, when said cover is moved to closed position, release and reset mechanism, and 65 manually operable means exteriorly of said cover for actuating the release and reset mechanism, said release and reset mechanism including a swingable member and a lost motion clutch control member wherein movement of the cover to 70 open position will be accompanied by movement

11

of the clutch to inoperative position and movement of the cover to closed position will cause delayed action of the clutch control member and effect complete clutch engaging action only when the cover has completed its closing movement.

12. In a wringer structure having a frame, a pair of cooperating rolls mounted in said frame, a housing mounting said frame and enclosing clutch and drive means operatively associated with said rolls, pressure means for said rolls, a cover enclosing the top of said frame, said cover, in closed position, applying said pressure means to said rolls, a release and reset mechanism mounted in said housing, and manually operable means exteriorly of said cover for actuating the release and reset mechanism, said mechanism including means for securing said cover in closed position against tension of said pressure means, and other means operable in one position to engage and secure said means in cover closed position, said other means including a lost motion connector for said clutch means wherein move-

ment of the cover to open position will be accompanied by movement of the clutch means to inoperative position and movement of the cover to closed position will cause delayed action of the clutch and effect complete clutch engaging action only when the cover has completed its closing movement.
